BOMB PROTECTOR

George J. Frederick, Portsmouth, Ohio

Application October 7, 1943, Serial No. 505,345

2 Claims. (Cl. 114—14)

My invention relates to ships and the like, and has among its objects and advantages the provision of an improved bomb protector.

In the accompanying drawings:

Figure 1 is a side view of a ship illustrating my invention applied thereto;

Figure 2 is a top view;

Figure 3 is an end view;

Figure 4 is an enlarged view of one of the supporting devices for the protector; and

Figure 5 is an enlarged view of a portion of the protector mesh.

In the embodiment selected for illustration, the ship 10 is provided with a plurality of upright supports 12 and horizontal supports 14 projecting laterally from the hull structure. The supports 12 and 14 carry a bomb protector net 16. Referring to Figure 5, this net comprises wire mesh 18 and reinforcing wires 20 woven in the mesh diagonally of the wires from which the mesh is woven. The wires 20 are looped, as at 22, to provide yielding ties or reinforcing wires in the mesh 18. The wires 20 are preferably of the cable type.

Figure 4 illustrates the manner in which the net 16 is tied to one of the supports 12. The net is similarly tied to all the supports 12 and 14, with the exception that the net does not surround the supports 14, since the net terminates substantially in the line of the supports 14. In Figure 4, the support 12 is provided with a plate 24 having upturned ears 26 perforated to slidably guide rods 28 connected with supporting cables 30. The supporting cables extend from the top ends of the supports 12 down to the outer ends of the supports 14.

Upon the rods 28 are mounted compression springs 32 abutting the ears 26 and flanges 34 attached to the rods 28. Thus the cables 30 are resiliently connected with the plates 24. These cables are woven through the mesh 18 and provide a framework for supporting the net in the configurations of Figures 1 through 3.

All the supports 12 are arranged in a straight line centrally and longitudinally of the ship 10 so as to provide a tapered contour when viewed

from the end. This provides a configuration which causes the bombs to be deflected off the net.

Without further elaboration, the foregoing will so fully illustrate my invention, that others may, by applying current knowledge, readily adapt the same for use under various conditions of service.

I claim:

1. In a wire mesh bomb-shield for water craft, a plurality of supporting standards rising vertically from points on the deck midway between the sides of the vessel, a plurality of supports extending out horizontally from the sides of the hull of the vessel, plates at the tops of the vertical supports having upturned perforated ears, guide rods having flanges and mounted to extend through the ears, springs about the guide rods abutting the flanges and ears to resiliently mount the same, the mesh shield extending from the vertical supports to the horizontal supports, and cables attached to each of the guide rods and extending diagonally and crossing each other and attached to the outer ends of the horizontal supports for supporting the shield, said cables being woven into the mesh of the shield.

2. In a reinforced wire mesh bomb shield for water craft, a plurality of spaced vertical supporting standards rising vertically from points on the deck midway between the sides of the vessel, a plurality of spaced supports extending out horizontally from the sides of the hull of the vessel, plates at the tops of the vertical supports having pairs of spaced radially positioned upwardly extending perforated ears, guide rods having flanges and mounted to extend through the ears with the

flange of each rod disposed between the ears, springs about the rods bearing against the flanges and ears to resiliently mount the guide rods, the mesh shield extending from and between the vertical supports and downwardly to the horizontal supports, cables attached to the rods and the outer ends of the horizontal supports respectively and extending diagonally and crossing each other for supporting the shield, and said cables being woven into the mesh of the shield.

3. In a reinforced wire mesh bomb shield for water craft, a plurality of spaced vertical supporting standards rising vertically from points on the deck midway between the sides of the vessel, a plurality of spaced supports extending out horizontally from the sides of the hull of the vessel, plates at the tops of the vertical supports having pairs of spaced radially positioned upwardly extending perforated ears, guide rods having flanges and mounted to extend through the ears with the flange of each rod disposed between the ears, springs about the rods bearing against the flanges and ears to resiliently mount the guide rods, the mesh shield extending from and between the vertical supports and downwardly to the horizontal supports, cables attached to the rods and the outer ends of the horizontal supports respectively and extending diagonally and crossing each other for supporting the shield, and said cables being woven into the mesh of the shield.

GEORGE J. FREDERICK
